ATTORNEY

UNITED STATES PATENT OFFICE

ADIEL Y. DODGE AND ROY S. SANFORD, OF SOUTH BEND, INDIANA, ASSIGNEES TO
BENDIX BRAKE COMPANY, OF SOUTH BEND, INDIANA, A CORPORATION OF ILLINOIS

BRAKE

Application filed November 17, 1927. Serial No. 233,754.

This invention relates to brakes and is illustrated as embodied in an internal expanding brake for an automobile.

An object of the invention is to facilitate the adjustment of a brake, and especially a brake of the "servo" type, in which there is a first shoe serving to apply a second shoe, by providing means for predetermining the relative applying movements of the two shoes, or their equivalents, so that an adjustment of the idle position of one of the shoes will cause a proportionate adjustment of the other shoe, thus permitting the use of a single adjustment on the brake.

15 In one very desirable arrangement, there is a guide or positioning device, illustrated as being mounted on the backing plate of the brake, and which engages a part of the friction means, such as a cam slot in one of the 20 shoes, in such a manner as to constrain the shoe to move both lengthwise and radially. Thus, as the shoe moves outward against the drum, it also moves lengthwise to apply the other shoe. In the arrangement illustrated in the drawing, the positioning device has a guide arranged in a slot in a part of the 25 friction means and it may also have parts arranged to serve as a steady rest preventing lateral movement of the brake shoes.

30 The above and other objects and features of the invention, including various novel and desirable details of construction, will be apparent from the following description of one 35 illustrative embodiment shown in the accompanying drawing, in which:

Figure 1 is a vertical section through the brake just inside the head of the brake drum and showing the brake shoes in side elevation;

40 Figure 2 is a partial section through the positioning device on the line 2-2 of Figure 1.

The brake selected for illustration includes a rotatable drum 10, at the open side of which 45 there is arranged a suitable support such as a backing plate 12, and within which is arranged the friction means of the brake. The illustrated brake is of the three-shoe type and utilizes a floating or "servo" shoe 14, connected by a floating pivot 16 to a secondary shoe

18, together with an auxiliary shoe 20, the 55 shoes 18 and 20 overlapping at their lower ends and being anchored on pivots 22. The brake is applied by suitable means such as a double cam 24, against the resistance of a return spring 26. If desired, an auxiliary return spring 28 may be connected to the unanchored end of the shoe 18 or to the lower 60 end of the shoe 14. Except as further described below, the brakes may, if desired, be 65 constructed substantially as fully described in Patent No. 1,567,716, granted Bendix Brake Company on December 29, 1925, on application of Adiel Y. Dodge.

An important feature of the present invention relates to the provision of means acting on one of the shoes 14 to predetermine the movement of these two shoes in applying the brake. In the illustrative embodiment of the invention there is a positioning device shown as including a post 30 secured to the 70 backing plate 12 by a nut 32 and having a portion 34 of reduced diameter projecting through a slot 36 in the stiffening web of the shoe 14. The post 30 is shouldered to engage a washer 38 on the backing plate side of the shoe, while another washer 40 is held against the opposite side of the shoe by a coil spring 42 confined between the washer 40 and a washer 44 held on the end of the positioning device by a cotter pin 46. Thus the 75 positioning device serves the additional function of a steady rest to prevent lateral movement of the brake shoe.

The positioning device is provided with a 80 guide 47 sleeved on the portion 34 of the positioning device and fitting as accurately as possible in the cam slot 36 formed in the web of the shoe 14. The axis of the cam slot 36 85 preferably extends lengthwise of the shoe and is so inclined with respect to the remaining brake parts as to insure that when the shoe 14 is operated by the cam 24 or its equivalent, it is constrained to move lengthwise as 90 well as radially, preferably in such a manner that the shoes 14 and 18 engage the drum substantially simultaneously. An important 95 advantage of this construction is in that fact that it eliminates the necessity of having any separate adjustment for the shoe 18, because 100

of the fact that turning the cam 24 to adjust the clearance of the shoe 14, in the customary manner, also forces the shoe 18 slightly outwardly against the drum and takes up on its clearance to compensate for wear.

5 If desired, the portion 34 of the positioning device may be made eccentric to the part passing through the backing plate 12 and the latter may be provided with a portion 48 to be turned by a wrench, thus providing a manufacturing adjustment when the brake is first set up. This adjustment moves toward and from the drum the predetermined path along which shoe 14 moves in applying the brake. 10 It is intended that thereafter no adjustment of the positioning device will be necessary.

15 While we have described one embodiment of the invention in considerable detail, it is not our intention to limit its scope to that particular embodiment or otherwise than by the terms of the appended claims.

20 We claim:

1. A brake comprising, in combination, a drum, a shoe which has a fixed anchor and 25 which is engageable with the drum, an unanchored shoe arranged to force the anchored shoe against the drum in applying the brake, one of the shoes having a guide part and a device engaging said part and with said anchor arranged to insure substantially simultaneous engagement of the two shoes with the drum.

2. A brake comprising, in combination, a drum, a shoe which has a fixed anchor and 30 which is engageable with the drum, an unanchored shoe arranged to force the anchored shoe against the drum in applying the brake, the unanchored shoe having a guide part and a device engaging said part and with said anchor arranged to insure substantially simultaneous engagement of the two shoes with the drum.

3. A brake comprising, in combination, a drum, and a pair of connected shoes within 35 the drum and the first of which is arranged to force the second against the drum in applying the brake, said first shoe being constrained to move lengthwise to operate the second shoe prior to its complete engagement with the drum.

4. A brake comprising, in combination, a drum, a pair of connected shoes within the drum and the first of which is arranged to force the second against the drum in applying the brake, and guide means engaging 45 said first shoe and constraining it to move lengthwise in applying the brake to act on the second shoe in a predetermined proportion to its radial movement toward the drum.

5. A brake comprising, in combination, a drum, a support adjacent the drum, a pair 50 of shoes engageable with the drum and the first of which is arranged to operate the second in applying the brake, and a guide engaging 55 the support and one of the shoes, and

arranged to predetermine the movement of both of the shoes.

6. A brake comprising, in combination, a drum, a support adjacent the drum, a pair of shoes engageable with the drum and the first 70 of which is arranged to operate the second in applying the brake, and a guide carried by the support and engaging the first shoe and arranged to constrain the first shoe to force the second shoe against the drum independently 75 of the action of the drum.

7. A brake comprising, in combination, a drum, a support adjacent the drum, a pair of shoes engageable with the drum and the first of which is arranged to operate the 80 second in applying the brake, and a cam device engaging one of the shoes and arranged to predetermine the relative movement of the two shoes in applying the brake.

8. A brake comprising a pair of connected 85 shoes, one of which is anchored, in combination with a guide which is capable of adjustment and which constrains the unanchored shoe to move in a predetermined path to apply the anchored shoe.

9. A brake comprising a pair of connected 90 shoes, in combination with a guide which is capable of adjustment and which constrains one shoe to move in a predetermined path to apply the other shoe.

95 In testimony whereof, we have hereunto signed our names.

ADIEL Y. DODGE.
ROY S. SANFORD.
